Calif., a corporation of Delaware

Filed Mar. 3, 1958, Ser. No. 718,666

2 Claims. (Cl. 229—3.5)

This invention relates to covered receptacles. More particularly, it is concerned with providing a novel covered and disposable receptacle made from relatively thin and flexible materials, such as aluminum foil, wherein unique means are provided for mounting and securing a cover to the receptacle.

Various covered receptacles made out of thin disposable aluminum foil which have been heretofore developed as a packaging medium for pies, cakes, frozen food products, and the like have not proven completely satisfactory. One of the reasons for this is because of the particularly arrangement used to secure the covers to such receptacles.

For economy, the receptacles or containers have been made of extremely thin, light metal foil such as aluminum foil of a gauge of between .002" to .0059" in thickness. The tops of these containers which receive the covers have been so constructed that their ragged edges had to be bent or otherwise manipulated by the fingers of the user in order to remove or replace the lid or cover of the container. Because of the very thin gauge material used, which in effect approximates razor sharpness, the householder frequently received finger cuts during the application or removal of the covers.

This characteristic of having a razor sharp edge on the container body at the point, where the lid is applied, is further aggravated in the case of aluminum foil containers because they are usually drawn on a press. During the drawing operation, the excess material in the metal foil blank from which the containers are made automatically takes the shape of folds or corrugations in the walls and top edges of the containers. These gatherings or folds of excess material are advantageous in the sense that they reinforce the relatively thin walls of the container. They are disadvantageous, however, in that they aggravate the razor sharpness of the free top edges of the drawn containers and thereby increase the possibility of inflicting serious injuries on the fingers of the user.

Accordingly, it is a primary object of this invention to provide a novel disposable container made of thin, flexible material such as a thin aluminum foil, wherein unique means are provided at the top of the container for securing a lid thereto, which means minimize injury to the user of the container.

It is a further object of this invention to provide a container body formed of readily disposable aluminum foil of a few thousandths inches in thickness wherein a unique arrangement is provided for securing a lid to the container body and wherein the means employed for securing the lid to the container body, when such means are not in use, do not interfere with the convenient stacking of the container body with another container body of similar construction.

It is another object of this invention to provide a unique container body made from aluminum foil which is of a sufficient thickness to be self-sustaining and yet is readily bendable by the fingers of the user and wherein the top reinforcing and stiffening rim of the container body is so constructed that all sharp edges, which would normally be contacted by the fingers of the user, are removed.

These and other objects of the instant invention are accomplished by providing a container for food products and the like made from thin, readily bendable yet self-sustaining aluminum foil of a few thousandths inches in

2

thickness. The container comprises a bottom and a side wall and the side wall terminates in a rim assembly. This rim assembly is so constructed that it includes an outwardly directed ledge element for receiving the marginal edge of a closure member. The ledge element also merges with a finger-engageable lip which is bendable inwardly and downwardly into engagement with the marginal edge of the closure member seated on the ledge element. This lip terminates in a reversely bent hem of a shorter height or width than the lip. The lip and hem are connected by a smooth reverse bend in the rim assembly whereby sharp edges on the rim assembly at the point of normal finger contact are eliminated.

Other objects and advantages of the instant invention will become more apparent from a review of the following detailed description when taken in conjunction with the appended drawings wherein:

FIGURE 1 is a perspective view of the covered container of the instant invention;

FIGURE 2 is a cross-section of the container shown in FIGURE 1 when taken along line 2—2 thereof and with the lip on the rim assembly of the container being shown in an up-raised position;

FIGURE 3 is an enlarged detailed sectional view of the rim portion of the container and discloses the manner in which the rim portion of the container is engaged by the user to force the lip of the rim portion into contact with a cover or closure member;

FIGURE 4 is another enlarged detailed sectional view of the rim portion and discloses the position of the lip on the rim portion at the time a closure member is secured to the rim portion;

FIGURE 5 is an enlarged sectional view of the rim portions of several containers nested one within the other; and

FIGURE 6 is an enlarged perspective view of the top portion of the container and shows the disposition of the hemmed edge of the rim, when it is brought into engagement with the container closure during application of the same to the container.

Although the container of the instant invention is shown as being of generally circular configuration, it is to be understood that it can be square, rectangular or otherwise shaped and that the sizes of the same may also be varied depending upon the results desired.

The container or receptacle 1 of the instant invention is generally comprised of a bottom 2 and one or more sidewalls 3. It is preferable that the sidewall be inclined or sloped outwardly for the purpose of facilitating stacking of similar containers one within the other as indicated in FIGURE 5. The wall 3 terminates in a roughly S-shaped rim assembly 4. The rim assembly 4 includes an outwardly directed planar ledge element 5 which acts as a seat for the marginal edge 6 of a closure or cover member 6.

Connected to the ledge element 5 by means of the bend 7 is a finger engageable lip 8 which is raised to a normally upstanding or semi-upstanding position during those times, when it is desirable either to apply or remove the closure member. When the lip is forced downwardly, it engages the marginal edge 6 of the closure member 6 applied to the container 1. As indicated in FIGURE 4, the space 9 between the ledge element 5 and lip 8 in effect forms a pocket 9 for receiving the marginal edge of the cover 6 when the lip 8 is forced down into a roughly horizontal position.

The lip 8 of the rim assembly 4 is advantageously provided with a turned back or hemmed edge or hem 10 connected to the lip 8 at the point A by a smooth reverse bend 11 as indicated particularly in FIGURE 3. The point A on the lip 8 is the place on the rim assembly where protection is most needed by the householder in

manipulating the lip 8 into and out of engagement with the cover 6' for the purpose of securing or removing the same from the container 1. The razor-like edge which normally occurs at this point readily inflicts injury upon the user because of the pressure applied by the user and some pressure must be applied to move lip 8 out of or into engagement with the container cover 6'.

By further reference to FIGURE 6, it will also be observed that the hemmed edge 10 and lip 8 of the container also possess the normal corrugations or gatherings which occur during the drawing of the container and the sharp edges formed by the corrugations are shown in exaggeration in FIGURE 6. These corrugations enhance the possibility of injury to the user of the container unless protection is afforded the user as in the case of the instant container.

The turned back or hemmed edge 10 on the container of the instant invention has another advantage in that it acts to rigidify the rim assembly by providing a lip member 8 of at least partial double thickness thereby forming a flat reinforced bead. This is in addition to the stiffness afforded by the corrugations or gatherings of the material during drawing. As noted in FIGURE 4, the outside hem 10, which lies in a plane substantially parallel to the plane of the lip 8, is adapted to be pressed substantially flat against the outside surface of the lip 8 when the lip engages the closure so as to effect a smoothing out of the corrugations in the lip and hem.

Finally, since the width or height of the hemmed edge 10 is not as large as that of the lip 8, which can also be advantageously inclined uniformly slightly outwardly, it facilitates the tight or close stacking of the containers one upon the other when the lip 8 is in a raised position in that it provides a minimum amount of material which would conflict with such nesting. This is indicated particularly in FIGURE 5. As further indicated in FIGURE 5 in the case of containers having a circular configuration the lip 8 can be considered as having a somewhat frusto-conical configuration. The edge 10 is also advantageously pressed tightly against the lip 8. Stated another way, the free edge X of hem 10 is spaced from the point of emergence Y of ledge 5 and lip 8 a sufficient distance whereby edge X acts as a nesting stop so that one container is held apart from an adjacent container and can be easily separated therefrom during nesting.

The cover 6' may be of paperboard, plastic, foil, or any combination thereof. If desired, the cover may also be provided with a transparent window in the center for the purpose of displaying the contents of the package. The container is preferably made from thin, flexible yet self-sustaining aluminum foil of between .002" and .0059" in thickness.

It is obvious that various changes can be made in the instant invention without departing from the spirit and scope thereof as defined in the appended claims.

What is claimed is:

1. A container for food products and the like comprising a receptacle made from thin readily bendable yet self-sustaining aluminum foil of a few thousandths of an inch in thickness, said receptacle comprising a bottom and an outwardly flaring side wall, said side wall terminating in a rim assembly, said rim assembly having corrugations formed therein as a normal incident to the fabrication of

the said rim assembly, and said rim assembly including an outwardly directed planar ledge for receiving the marginal edge of a closure, said ledge terminating in a normally upstanding finger engaging lip which flares uniformly slightly outwardly and which is bendable inwardly and downwardly into engagement with the marginal edge of the said closure when the closure is seated on the said ledge, and said finger engaging lip finally terminating in a reversely bent outside hem which lies substantially flat against the outside surface of said lip to form a flat reinforcing bead, said reversely bent hem being of a shorter height than the said lip such that the free edge of the hem is spaced from the point of emergence of the ledge and lip and acts as a nesting stop for the container when it is nested with another container of similar configuration, said hem and lip being connected by a smooth reverse bend in said lip, whereby sharp edges on the lip at the normal point of finger contact are eliminated and the said hem also being adapted to be pressed substantially flat against the outside surface of the lip when the lip engages the said closure so as to effect a smoothing out of the corrugations in the lip and hem and a rigidifying of the closure engaging rim assembly.

2. A container for food products and the like comprising a receptacle made from thin readily bendable yet self-sustaining aluminum foil of a few thousandths of an inch in thickness, said receptacle comprising a bottom and an outwardly flaring side wall, said side wall terminating in a rim assembly, said rim assembly having corrugations formed therein as a normal incident to the fabrication of the said rim assembly, and said rim assembly including an outwardly directed planar ledge for receiving the marginal edge of a closure, said ledge terminating in a normally upstanding finger engaging frusto-conical lip which flares slightly outwardly and which is bendable inwardly and downwardly into engagement with the marginal edge of the said closure when the closure is seated on the said ledge, and said finger engaging lip finally terminating in a reversely bent outside hem which lies substantially flat against the outside surface of said frusto-conical lip to form a flat reinforcing bead while being of a shorter height than the said lip such that the free edge of the hem is spaced from the point of emergence of the ledge and lip and acts as a nesting stop for the container when it is nested with another container of similar configuration, said hem and lip being connected by a smooth reverse bend in said lip, whereby sharp edges on the lip at the normal point of finger contact are eliminated and the said hem also being adapted to be pressed substantially flat against the outside surface of the lip when the lip engages the said closure so as to effect a smoothing out of the corrugations in the lip and hem and a rigidifying of the closure engaging rim assembly.
